FUSE

Percy L. Spencer, West Newton, Mass., assignor
to Raytheon Production Corporation, Newton,
Mass., a corporation of Delaware

Application January 21, 1942, Serial No. 427,612

3 Claims. (Cl. 200—125)

This invention relates to improvements in electrical fuses.

An object of this invention is the provision of a fuse for precise operation on small currents.

Another object of this invention is the provision of a fuse which will of itself tend to limit the current to a predetermined value.

A further object of this invention is the provision of a multiple fuse device which is so constructed that when one fuse element has been destroyed by an overload of current others are available without requiring the substitution of another fuse device.

A further object of this invention is the provision of a fuse adapted to be arranged in a 15 radio tube socket.

Still another object of this invention is the provision of a fuse device which is simple to construct and reliable in operation.

A further object of this invention is the provision of a fuse device which can be constructed at relatively low cost.

Other and further objects and advantages of this invention, and the hereinbefore mentioned objects, will become clear from the following description of an exemplification thereof, reference being had to the drawing, in which

Fig. 1 is a top plan view of a fuse device embodying my invention;

Fig. 2 is a perspective view, partly broken away, of said fuse device and includes a plan view of a socket; and

Fig. 3 is a schematic diagram of a circuit within which said fuse device is adapted to be arranged.

The fuse device 1 consists of a glass envelope 2 having a bottom wall consisting of a stem or base 3. A plurality of lead-in rods 4 are sealed through said stem 3. These lead-in rods are made of some metal which readily seals to the glass of said stem, and may conveniently be made of chrome iron. The lead-in rods 4 are disposed in a circle concentric with the center of the stem 3. These lead-in rods are also rigid so that in the completed form of the tube they serve as the external contact pins adapted to be inserted into a cooperating tube socket 5. The bottom of the glass envelope 2 is surrounded by a guard shell 6 held in place on the envelope by means of a ring of cement 7. The guard shell 6 is provided with sufficiently large openings around each of the lead-in rods 4 so that electrical contact between the shell 6 and the rods 4 is effectively prevented. The envelope 2 is provided at the central portion of the base 3 with an exhaust opening communicating with an exhaust tube 8.

The envelope is exhausted through the exhaust tube to provide a high vacuum therein.

Around the exhaust tube 8 a tubular member 9 is provided, said tubular member being adapted to be arranged within the positioning opening 10 in socket 5. The tubular member 9 thus serves as a guide in centering the fuse device when inserting it in socket 5. The lead-in rods 4 are adapted to fit into openings 11 within said socket and make contact with the contacts 12 therein.

The socket 5 is a radio tube socket. By the term "radio tube socket" I mean herein and in the claims the standard radio receiving tube type of socket now in common use. The socket herein illustrated is known as the "octal" type and has eight openings 11 adapted to receive eight contact pins 13 which are the protruding portions of lead-in rods 4.

The fusible elements are adapted to be secured to the upper portions 14 of lead-in rods 4. For this purpose I prefer to use a wire having a relatively high positive temperature coefficient of resistivity. A wire 15 made of iron or nickel has been found satisfactory. This wire is wound around the eight upper portions 14 of the lead-in rods 4, leaving a space between two of them 16 and 17, so as to prevent a complete turn from being made. The wire 15 may be secured to the upper portions 14 of the lead-in rods 4 by welding said wire thereto. Each portion of the wire 15 between the upper portions 14 of the lead-in rods 4 serves as a separate fuse except between upper portions 16 and 17 between which the wire does not run. It will be noted therefore that each of the upper portions 14, except 16 and 17, serves as a common conductor for two fuse elements.

As stated hereinbefore the envelope 2 is highly evacuated. Therefore the heat developed by passing the current through any of the fuse elements is not dissipated. Thus, when the current in the wire rises, the temperature of the wire increases in an amount that can be precisely determined. This permits accurate design for precise operation of such fuse devices. Furthermore because of the high positive temperature coefficient of resistivity of the material employed the wire increases its resistance as it becomes hotter. The wire therefore tends to limit the amount of current passing therethrough. Furthermore the increased resistance generates more heat, raising the temperature of the wire, to thereby produce cumulative action which causes rapid burn-out of the fuse wire.

Two of the contacts 12 of socket 5 are arranged in a circuit to be protected from current over-

loading. A source of E. M. F. 18, and a load 19 are arranged in series with each other and connected to said contacts. When the fuse device 1 is arranged in the socket 5 using the tubular member 9 as a centering guide and inserting said tubular member 9 within the opening 10 in said socket, the contact pins 13 touch the contacts 12.

In the ordinary radio tube socket, such as socket 5, a keyway is provided for receiving the key customarily provided on the tubular positioning member projecting from the base of the radio receiving tube. Since no key is provided on the tubular member 9 the fuse device 1 can be placed in any position so that any two adjacent contact pins 13 may be arranged to touch the contacts 12 which are connected in the circuit to be protected. It will be readily seen that when one of the fuse elements burns out said fuse device may be raised slightly out of the socket so that the contact pins 13 are cleared of the top of said socket and the fuse device may then be rotated to bring contact pins connected with an unfused fuse element into position for insertion in those openings 11 which have their contacts 12 connected to the circuit to be protected. Since the lead-in rods 4 are spaced an equal distance from each other and since the wire 15 is of uniform cross section it will be apparent that the fuse element between any two of the lead-in rods will be equal to that between any two others. It will, of course, be understood that contact pins 13 connected with upper portions 16 and 17 are not to be arranged in contact with the contacts 12 which are connected to the circuit to be protected since there is no fuse wire between these two upper portions.

In actual practice it has been found that fuse devices such as hereinbefore described are simple to construct and require no special skill. Such fuses although made by relatively unskilled hands have been found to be reliable in operation and extremely uniform. For example, a number of fuse devices made in the manner hereinbefore described included a fusible wire having a diameter of .00046 of an inch and was three inches in length. This wire was wound round the lead-in rods 4 and welded to said rods to form seven separate fuse elements. The wire used was made of nickel with approximately one per cent of other metals, including carbon. This was a 25 millampere fuse. Tests made with a number of fuses of this kind showed a variation of between 1 1/2 to 2 millamperes plus or minus, at which each of the fuse elements would blow. The variation between the fuse elements in any one fuse device was no greater than the foregoing.

While I have described a specific embodiment of my invention it will be understood that the details thereof may be varied without departing from the spirit thereof. For example, instead of a round fuse wire a flat ribbon may be used.

Changes in the shape of the fuse device or in the manner of connecting the fuse elements and/or its conducts will readily suggest themselves. Other changes will be apparent from the foregoing description to anyone versed in the art. Therefore it is accordingly desired that the appended claims be given a broad interpretation commensurate with the scope of the invention within the art.

What is claimed is:

1. A multiple fuse unit comprising an insulating base, a plurality of pins secured in said base and forming contact prongs projecting therefrom, said prongs being arranged in a circle with each prong equidistant from its adjacent prongs, and a unitary fuse member secured and electrically connected at spaced intervals thereof to each of said pins to thereby form a plurality of fuse elements, said unit being adapted to be manually manipulated to bring said contact prongs into contact with cooperating contacts in a socket.

2. A multiple fuse unit for arrangement in a socket, said socket having receiving openings with contacts therein, comprising a plurality of pins secured in said base and forming contact prongs projecting therefrom, said prongs being arranged in a circle with each prong equidistant from its adjacent prongs, said prongs being adapted to fit into the receiving openings in said socket and make contact with the contacts therein, and a unitary fuse member substantially circumferentially arranged about said pins, said member being secured and electrically connected at spaced intervals thereof to each of said pins to thereby form a plurality of fuse elements.

3. In combination a multiple fuse unit and a socket in which said unit is adapted to be arranged, said socket having receiving openings with contacts therein and a central positioning opening, said unit comprising an insulating base, a plurality of contact pins fixed in and extending above and below said base, said pins being arranged in a circle with each pin equidistant from its adjacent pins, said pins being adapted to fit into the receiving openings in said socket and make contact with contacts therein, a circle of fused elements electrically connecting said pins and a centrally located positioning member projecting from beneath said base and of greater length than the positions of said contact pins extending below said base, said positioning member being adapted to be journaled in the socket positioning opening whereby said unit member may be raised from the socket without completely withdrawing the positioning member and may be rotated so that the contact pins may be inserted in different receiving openings of said socket to thereby place different fuse elements in electric contact with different sets of said contacts.

PERCY L. SPENCER.
